Primary Examiner — Lauren Calve(74) *Attorney, Agent, or Firm* — Zachary D. Renstrom(57) **CLAIM**

The ornamental design for a garbage bag dispenser, as shown and described.

DESCRIPTION

FIG. 1 is a perspective view of a garbage bag dispenser showing my new design;

FIG. 2 is a top view thereof;

FIG. 3 is a perspective view thereof shown in environmental use;

FIG. 4 is a perspective view thereof shown in a second environmental use;

FIG. 5 is a perspective view thereof shown in a third environmental use; and,

FIG. 6 is a perspective view of the garbage bag dispenser of FIG. 1.

The broken lines shown represent unclaimed subject matter and form no part of the claimed design.

1 Claim, 4 Drawing Sheets(56)
